UNITED STATES PATENT OFFICE.

ARTHUR JAMES VEALL, OF SOUTH YARRA, VICTORIA, AUSTRALIA.

QUICK-ACTION ELECTRIC SWITCH.

Application filed March 9, 1926, Serial No. 93,403, and in Australia March 17, 1925.

This invention relates to improvements in quick action electric switches and refers especially to "pull switches" of the type usually located on ceilings and operated by pulling on a cord.

Hitherto it has been proposed to make a one-way or two-way quick action or snap switch of the tumbler type with a bridge piece pivotally supporting a member carrying the blades or movable contacts and in arranging an operating lever and a T-shaped member formed with a stem surrounded by a compression spring whereby when the lever is actuated the movable contact members move with a dead-centre quick action in the opposite direction. This type of switch enables a quick "make and break" to be effected but it cannot be satisfactorily adapted for use in cases where the switches are required to be placed on a ceiling or other inaccessible position.

The object of the invention is to provide an electric switch of the quick action type embodying simple and durably constructed mechanism operable by a pull cord whereby the contacts will have a quick make and break or non-controllable action and provide efficient service over a lengthy period.

I accomplish the above mentioned object by providing a switch having fixed contacts fitted to a base supporting a bridge piece furnished with contacts adapted to be oscillated in opposition to spring pressure by the operation of toggle members receiving their motion from a crank associated with a pulley which is rotated by pulling on a cord.

The switch can be of the one-way or two-way type and the pulley can be connected to the member supporting the crank by pawl and ratchet mechanism and acted upon by a spring to return it to its normal position after each operation.

In order that the invention, the object and nature of which have been clearly set forth, may be readily understood reference will now be had to the accompanying sheets of explanatory drawings wherein—

Figure 1 is a view in sectional elevation of a switch constructed in accordance with the present invention.

Figure 2 is a view in sectional elevation of the switch taken at right angles to Figure 1.

Figure 3 is a view in plan of the switch.

Figures 1 and 2 represent sectional views taken on the dotted lines 1—1 and 2—2 of Figure 3.

Figures 4, 5 and 6 are views illustrating certain constructional details which herein-after will be fully described.

Figure 7 is a view in elevation showing certain modifications in the construction and arrangement of parts of the switch.

Figure 8 is a view of the switch shown in Figure 7 and viewed at right angles thereto.

In Figures 7 and 8 the operative parts of the switch are shown in full lines and the base and cover are indicated by broken lines.

Figures 9 and 10 are views similar to Figures 1 and 2 and show further modifications of details in the construction of the switch.

In these drawings the same characters of reference have been employed to indicate the same or corresponding parts in the different views and the numeral 1 designates a base of porcelain or other insulating material which is provided with a recess 2 in which are supported spring contact jaws 3 electrically associated with socket or screw terminals 4 adapted to receive the ends of lead and return wires for supplying current from a main.

A bridge piece 5 is secured to the top of the base 1 and to the lower part of the bridge piece is pivoted the ends of a U-shaped member 6 which supports movable contact blades 7 so arranged that when the U-shaped member is oscillated the blades will be moved into and out of contact with the spring contact jaws.

The bridge piece 5 is secured to the base by means of screws 8 and the sides thereof can be provided with extensions 9 which are adapted to be seated in recesses 10 in the base to afford additional rigidity. The recesses 10 may be arranged at one side of holes 11 for accommodating screws for securing the base to a support.

The movable contact blades 7 are insulated and project laterally from the looped or free end of the pivoted U-shaped member 6. A lug 12 is formed on the looped part of the U-shaped member and this lug is adapted to be engaged by jaws 13 formed on a head on one end of a rod 14. The opposite end of the rod 14 passes through a hole in a rocking member 15 carried by an oscillatable lever 16 having its outer end pivotally supported on the bridge piece.

The free end of the oscillatable lever 16 is formed with jaws 17 having opposed holes 110 adapted to accommodate trunnions 18 on the rocking member embracing the rod,

A compression spring 19 surrounds the rod 14 and is adapted to bear at one end against the head provided with the jaws 13 and at the opposite end against the rocking member 15.

The oscillatable lever 16 is slotted at 20 to receive a pin 21 mounted eccentrically on a disc 22 carried on a pin 23 supported by one side of the bridge piece. The disc 22 is accommodated in a recess 24 formed concentrically in one side of a grooved pulley 25 which is adapted to rotate on the supporting pin and the adjacent faces of the disc and pulley are provided with a spring pawl 26 and recesses 27 whereby when the pulley is rotated in one direction a corresponding rotation will be imparted to the disc and the lever 16 will be oscillated to actuate the movable contacts 7.

20 The spring pawl 26 is accommodated in an annular depression 28 in the bottom of the recess 24 and one end is adapted to engage with the recesses 27 in the disc when the pulley is rotated. When the pulley is returning to its normal position the free end of the spring pawl 26 ratchets freely over the recesses 27.

25 The fixed end of the spring pawl 26 passes through a slot in the pulley 25 and the projecting end 29 is formed with a hole for the purpose hereinafter described.

30 A cord 30 is attached to the periphery of the pulley and passes around the same and through a cover 31 secured to the base or 35 through a hole in the bridge piece. The free end of this cord is provided with a button, tassel, or the like in the usual way to enable the same to be conveniently grasped to pull the cord to rotate the said pulley.

35 A torsional spring 32 is mounted on a boss 33 on the pulley and this spring is adapted to exert pressure on the said pulley in opposition to the direction in which the cord is pulled to operate the switch. One end of the torsional spring 32 passes through the hole in the fixed end of the spring pawl 26 and the opposite end is bent over the outer part 45 of the bridge piece 15, see Figures 2 and 5.

40 Co-acting stops are provided on the pulley and bridge piece to limit the movement of the pulley when the cord is pulled and to ensure it returning to its normal position by the action of the spring 32 when the cord is released.

45 The co-acting stops may comprise a lateral projection 34 on the pulley and a tail 35 on the end of the spring 32 secured to the bridge piece. The tail of the spring 32 is extended to lie in the path of movement of the projection 34 and the said tail is sufficiently resilient to absorb shock and to eliminate noise when struck by the said projection upon the release of the cord.

50 The rod 14 provided with the compression spring 19 and the U-shaped member 6 nor-

70 mally lie at an angle to each other and when the oscillatable lever is moved by the rotation of the disc to place the rod and U-shaped member in line with each other the spring 19 will be compressed and during the further movement of the oscillatable lever and rod the pressure exerted by the spring will cause the movable contact blades to be moved into or out of engagement with the spring contact jaws with a very rapid motion.

75 The toggle action of the lever and rod is sufficiently powerful to overcome the resistance of a compression spring strong enough to ensure the movable contact members being operated with a quick action when the pivotal connection between the rod and the U-shaped member is moved past its dead centre position.

80 Provision is made for positively opening and closing the contacts of the switch should the spring 19 become weakened or the movable blades become jammed between the spring jaws. This object is effected by providing an extension 36 on one side of the U-shaped member so that it will lie between laterally projecting striking lugs 37 on the free end of the oscillatable lever. The striking lugs 37 are so disposed that in the event of the spring 19 failing to function they will contact with the extension 36 and the blades 95 will be moved into their opened or closed position by the further pull on the cord. The lugs 37 are arranged so that they will not contact with the extension 36 in the event of the spring functioning correctly.

100 In the arrangement of the parts shown in Figures 7 and 8 the rod 14 is disposed centrally between the arms of the U-shaped member 6 and the jaws 13 thereon are pivoted to an arm 38 on a transversely disposed pivot 105 pin 39 which is formed integrally with a lever 40 having a slot 41 engaging the pin 21 disposed eccentrically on the disc 22. The slotted lever 40 projects downwardly between one side of the bridge piece 5 and the adjacent side of the pulley 25. The upper end of the rod 14 in this instance passes through a hole in the looped end of the U-shaped member 6 and the said hole may be provided with a lining of insulating material.

115 The bridge piece can be made shorter than shown in Figures 2 and 8 and mounted on projections 42 formed on the base; see Figures 9 and 10. When the bridge piece is mounted on the projections 42 the pivots of the U-shaped member are seated in recesses 43 formed on the opposed inner faces of the said projections 42 and when the rocking member 15 is made of non-conducting material the movable contacts are effectually insulated 120 from the bridge.

125 In Figures 9 and 10 the invention is shown applied to a double pole or two way switch and a modification of the means for positively operating the switch is illustrated.

The modification in the means for positively actuating the movable contacts consists in providing a forked extension 36' on one arm of the U-shaped member which is 5 adapted to lie in the path of an extended trunnion 15' on one side of the rocking members.

The cover 31 for the switch is formed out of sheet metal and is secured to the bridge 10 piece by a screw pin and nut 50, see Figures 1 and 2.

Alternatively the cover 31 can be secured to the bridge piece by a resilient member such as a spring 51 mounted on the bridge piece 15 and engaging holes or recesses 52 in the cover. The resilient member frictionally engages the recesses in the sides of the cover whereby the cover can be attached and detached simply by pushing it on to and pulling it 20 from the bridge piece.

In lieu of arranging the pull cord 30 to pass from the pulley through a hole in the top of the cover it can be passed through a hole 53 formed in one side of the base thereby 25 enabling the said pull cord to be operated in a radial direction (see dotted lines in Figures 1 and 3). This arrangement of the pull cord will be found convenient when a switch 30 is located high up on a wall or other vertical structure.

Each time the cord is pulled to partially rotate the pulley the pivotal connection between the rod 14 and the oscillatable lever 16 will be oscillated to cause the said rod and 35 lever to assume an opposite angle to which they were disposed prior to pulling on the said cord and the contact blades to be moved either into or out of engagement with the fixed contacts.

The parts of the switch are so disposed with relation to each other than when the movable contact blades are either in their "make" or "break" positions the operation of 40 the pulley by pulling on the cord will cause the eccentrically disposed pin on the disc or pulley to actuate the toggle members 6 and 14 to move the switch blades in a reverse direction to which they were operated upon the previous pull of the cord, in other words, 45 when the switch has been operated and the cord released to allow the pulley or parts attached thereto to return to their normal positions, the remaining parts of the switch are in their correct relative positions to be again 50 operated.

When the pulley is returning to its normal position after actuating the toggle members to place the movable contacts into a "make" 55 or "break" position the resistance of the compression spring on the rod will prevent rotation of the disc or pulley and the ratchet members will move freely past each other under the influence of pressure exerted by the torsional or tension spring acting thereon.

In the foregoing specification I have de-

scribed a switch embodying the preferred forms of construction but as various modifications, alterations and rearrangement of parts may be made therein without departing from the spirit and scope of the invention I 70 do not wish to be confined to the examples given which are purely illustrative and in nowise limitative.

I claim:—

1. A switch comprising a base, fixed contacts on the base, a bridge piece fitted to the base, a U-shaped member pivoted to the bridge piece, a pulley rotatively mounted on the bridge piece, a pull cord attached to and passing around the periphery of the pulley, 75 an oscillatable lever having one end pivoted to the bridge piece, a pin disposed eccentrically to the pulley, a slot in the oscillatable lever engaging the eccentrically disposed pin, a rod having its free ends movably connected 80 to the U-shaped member and to the free end of the oscillatable lever, and a compression spring surrounding said rod, an extension on one arm of the U-shaped member and lugs on the free end of the oscillatable lever adapted 85 to contact with the extension on the U-shaped member to positively actuate the movable contacts when the switch is operated.

2. A switch comprising a base, fixed contacts on the base, a bridge piece fitted to the 90 base, a U-shaped member pivoted to the bridge piece, a pulley rotatively mounted on the bridge piece, a pull cord attached to and passing around the periphery of the pulley, 95 an oscillatable lever having one end pivoted to the bridge piece, a pin disposed eccentrically to the pulley, a slot in the oscillatable lever engaging the eccentrically disposed pin, a rod having its free ends movably connected 100 to the U-shaped member and to the free end of the oscillatable lever, and a compression spring surrounding said rod, an oscillatable lever having one end pivoted 105 to the bridge piece, a pin disposed eccentrically to the pulley, a slot in the oscillatable lever engaging the eccentrically disposed pin, a rod having its free ends movably connected 110 to the U-shaped member and to the free end of the oscillatable lever, and a compression spring surrounding said rod, a forked extension on one arm of the U-shaped member, a projection on the oscillatable lever adapted to engage with one or other of the members 115 on the forked extension to cause the movable contacts to be positively actuated when the switch is operated.

3. A switch comprising a base, fixed contacts on the base, movable contacts co-operating therewith, a bridge piece fitted to the base, a U-shaped member pivoted to the bridge piece, a pulley rotatively mounted on the bridge piece, a pull cord attached to and passing around the periphery of the pulley, 120 an oscillatable lever having one end pivoted to the bridge piece and having a slot therein, a pin disposed eccentrically to the pulley and engaged by the slot in the oscillatable lever, a rod having its free ends movably connected 125 to the U-shaped member and to the free end of the oscillatable lever, a compression spring surrounding the said rod, a jaw on the free end of the oscillatable lever, a rocking member mounted in the jaw and having a hole 130

therein, a hole in the locking member loosely engaging one end of the rod, and a pivotal engagement between the opposite end of the rod and the U-shaped member carrying the movable contacts.

4. In a switch of the class described having toggle members adapted to be operated in opposition to spring pressure to place movable contacts in to and out of engagement with fixed contacts by a pulley, a pull cord for rotating said pulley; a spring for re-setting the pulley, an oscillatable lever having a slot therein, an eccentrically disposed member associated with the pulley and oscillatable lever, a disc rotatively mounted in a recess formed in one side of the pulley, a spring pawl fitted to the pulley and adapted to engage recesses

in the disc, a pin disposed eccentrically on the disc and passing through the slot in the oscillatable lever, said pulley having a hole in its side, an angle shaped piece on the fixed end of the spring pawl passing through a hole on the side of the pulley, a torsional spring having one end engaging the projecting portion of the fixed end of the pawl and the opposite end secured to a fixed part of the switch, a stop on the pulley, and a tail piece on the end of the spring secured to the fixed part of the switch, and arranged to lie in the path of movement of the said stop.

In witness whereof I hereunto affix my signature.

ARTHUR J. VEALL.
